[57] ABSTRACT

[22] Filed: Dec. 19, 1973

Single crystals consisting of various compositions from the quaternary silicate system $Al_2O_3-CaO-MgO-SiO_2$ are grown from the melt. The physical and chemical properties of the single crystal silicates, including akermanite ($Ca_2MgSi_2O_7$), cordierite ($Mg_2Al_4Si_5O_{18}$), gehlenite ($Ca_2Al_2SiO_7$) and, mullite ($Al_6Si_2O_{13}$), make the silicates useful, for example, as substrates for epitaxial semiconductor films.

GROWTH OF INCONGRUENTLY MELTING CRYSTALS FROM A QUATERNARY SILICATE SYSTEM USING THE CZOCHRALSKI METHOD

BACKGROUND OF THE INVENTION

1. Field of the Invention

This invention relates to compositions selected from the quaternary silicate system $\text{Al}_2\text{O}_3\text{-CaO-MgO-SiO}_2$, to the growth of single crystal compounds from this system (hereafter termed "silicates"), and to the utilization of the single crystal silicates, including their use as substrates for epitaxial semiconductor films.

2. Description of the Prior Art

The epitaxial silicon on sapphire (SOS) technology initiated by U.S. Pat. No. 3,393,088, entitled "Epitaxial Deposition of Silicon on Alpha Aluminum," issued to H. M. Manasevit and W. I. Simpson, and assigned to the common assignee, has contributed to the rapid growth of silicon semiconductor technology, particularly in the area of microelectronic circuit applications. With the development of this technology, however, there has been imposed increasingly diverse and stringent requirements regarding the physical and chemical properties of the substrate materials. In short, the achievements of silicon on substrate technology and the potential for further application of the technology require the development of additional substrate materials that are compatible with epitaxial films.

Sapphire, of course, has achieved wide acceptance as a substrate material. To date, the focus of attention has been on spinel, as well as sapphire, substrate materials. However, properties such as thermal shock susceptibility and thermal expansion impose limitations on the fabrication parameters and the operating environments of microelectronic circuitry that uses sapphire or spinel substrates. For example, as a result of thermal stability limitations, the surfaces of spinel substrates may decompose during film deposition.

The quaternary silicate system $\text{Al}_2\text{O}_3\text{-CaO-MgO-SiO}_2$ includes compositions that have physical and chemical properties, e.g., thermal expansion coefficients and compatibility with silicon films, that indicate the silicates would be well suited for use as substrates for silicon films and other semiconductor films if the silicates could be grown as single crystals.

The single crystal silicates are not limited to use as substrates. For example, the heat resistant qualities of mullite make it quite suitable for use in heat shields, high temperature particle filters, and so forth.

Various members of the silicate system are used in polycrystalline form, e.g., in the ceramics industry. Several techniques, such as flame fusion, have been used to grow single crystal silicates. However, none of the known techniques has proved satisfactory for the production of large, single crystal boules for device-quality substrates. Growth from the melt, which is used to grow single crystals of materials such as sapphire, has not been successfully applied to the silicates. This lack of success is perhaps due in part to conflicting data in the literature regarding whether the most widely used and best characterized silicate — mullite — is incongruently melting and, therefore, incapable of being successfully grown from the melt.

It may be appreciated that it is highly desirable to develop a technique for growing high quality, monocrystalline material from the compositional boundaries of the above-described quaternary silicate system.

SUMMARY OF THE INVENTION

A single crystal silicate is grown by (1) forming a melt containing weight percentages of the compounds Al_2O_3 , MgO , CaO , and SiO_2 corresponding to the weight percentages of the particular silicate compound that is to be grown; (2) inserting a rotating seed crystal having the composition of the particular silicate compound below the surface of the melt to initiate growth thereon; and (3) forming a crystal on the seed by withdrawing the seed from the melt using predetermined translation and rotation rates.

Crystals grown in the above-described manner are monocrystalline, of device quality, and possess excellent properties, such as thermal and chemical stability, for use as substrates in semiconductor compounds.

BRIEF DESCRIPTION OF THE DRAWING

FIG. 1 is a cross-sectional representation of furnace apparatus that is suitable for growing single crystal silicate crystals in accordance with the method of the present invention.

FIG. 2 is a cross-sectional representation of a composite comprising an epitaxial film on a single crystal silicate substrate grown in accordance with the present invention.

DETAILED DESCRIPTION

As discussed previously, the literature is in conflict as to whether the silicate mullite ($\text{Al}_6\text{Si}_2\text{O}_{13}$) is incongruently melting. If mullite is incongruently melting, it would be extremely difficult to grow crystalline mullite from the melt. That is, and assuming mullite to be incongruently melting, if a mix containing proper weight percentages of constituents to form mullite is brought to the melting point, the composition decomposes into liquid and solid phases, i.e., liquid plus solid corundum. If the charge is molten and cooling is initiated, corundum will begin precipitating from the liquid at the liquidus point. The liquid will then become enriched in SiO_2 . The precipitation process continues until the entire system is solidified. At no time will the mullite form a crystalline phase.

However, experimental work by the applicants suggested that, even if mullite is incongruently melting, chemical kinetic considerations would allow the growth of mullite from the melt. That is, the precipitation of corundum from the molten charge is very slow. Thus, by rapidly cooling the charge, the precipitation of corundum is avoided and crystalline mullite growth does occur. This finding has been applied to successfully grow single crystal mullite from the melt using a modified Czochralski growth technique. In addition, the method of growth has been shown to be applicable to other members of the quaternary silicate system $\text{Al}_2\text{O}_3\text{-CaO-MgO-SiO}_2$. The accompanying Table lists other members of the silicate system.

Referring now to FIG. 1, there is shown a furnace apparatus 10 suitable for growing silicate single crystals from the melt using the method of the present invention. The furnace apparatus 10 includes a base 11 that is supported in a conventional manner and supports a tube 12 of a suitable refractory material, such as ceramic. The ceramic tube 12 is heated by an RF heating coil 13 that is actuated by a conventional power supply (not shown). The tube 12 is packed with zirconia sand 14 for supporting and insulating a crucible 16. The cru-

cible, which is typically formed from iridium, contains a molten charge or melt 17, from which a crystal 18 is grown. The apparatus 10 also includes a crystal puller 19 that is controlled by conventional means (not shown) for both translational and rotational movement within tube 20. A small tube 21 extends downwardly from the bottom of the crucible 16 and through an aperture 22 in the base 11 so that a thermocouple (not shown) may be brought into proximity to the crucible 16 and used to control the operation of the coil power supply and, thus, effect heating the coil 13. FIG. 1 illustrates only one possible configuration of crucible support and insulation. Other arrangements could be used with equal benefit.

TABLE

Properties of Silicates of the System $\text{Al}_2\text{O}_3\text{-CaO-MgO-SiO}_2$

Silicate Compound	Crystal Structure	Melting Point (°C)	Hardness (Moh)	Thermal Expansion	Density (gm/cm³)
Akermanite ($\text{Ca}_2\text{MgSi}_2\text{O}_7$)	Tetragonal	1454	5-6		2.94
Cordierite ($\text{Mg}_2\text{Al}_4\text{Si}_5\text{O}_18$)	Orthorhombic	1368	7-7.5	$3.23\text{-}3.35 \times 10^{-6}$	2.6-2.66
Fayalite (Fe_2SiO_4)	Orthorhombic	1205	3.2-4.4	2.36×10^{-6}	
Forsterite (Mg_2SiO_4)	Orthorhombic	1890	6-7	10.6×10^{-6} for 20-800°C	3.21-3.33
Gehlenite ($\text{Ca}_2\text{Al}_2\text{Si}_3\text{O}_7$)	Tetragonal	1590	5-6		2.9-3.1
Larnite (Ca_2SiO_4)	Monoclinic	~2125			3.28
Merwinite ($\text{Ca}_3\text{MgSi}_2\text{O}_8$)	Monoclinic	~1680	6		3.15-3.31
Monticellite (CaMgSiO_4)	Orthorhombic	~1405	5		3.2
Sapphirine ($\text{Mg}_2\text{Al}_4\text{Si}_2\text{O}_12$)	Monoclinic	~1450	7.5		3.4-3.5
Mullite ($\text{Al}_6\text{Si}_2\text{O}_{13}$)	Orthorhombic	~1860	6.7		3.15-3.26

The method of growing single crystal silicate compounds from the melt comprises the steps of (1) forming a melt 17 consisting of the compounds Al_2O_3 , CaO , MgO , and SiO_2 in weight percentages corresponding to those of the desired crystalline composition, the melt being formed within the crucible 16 and at a temperature just above the melting point of the composition; (2) raising the temperature of the melt to the extent necessary to provide a homogeneous melt; (3) inserting at least a portion of a seed crystal into the melt to initiate growth of the silicate crystal; (4) pulling the seed crystal from the melt at predetermined translational and rotational rates, while controlling the temperature of the melt, to grow a crystal 18 of predetermined length and diameter; (5) pulling the crystal from the melt at an increased rate; and (6) cooling the crystal and melt to room temperature.

Application of the above-described method is illustrated by the following examples:

EXAMPLE 1

Mullite ($\text{Al}_6\text{Si}_2\text{O}_{13}$)

A charge comprising 71.795 weight percent Al_2O_3 and 28.205 weight percent SiO_2 was melted in the iridium crucible 16 at the 1860°C melting point of mullite, then elevated to about 1865°C to provide a homogeneous melt 17. A mullite seed crystal affixed to a lower end 23 of the crystal puller 19 was then lowered to a position just below the melt surface using crystal puller rotation of about 30 rpm.

Upon initiation of mullite single crystal growth on the seed crystal as a result of the temperature differential between the seed crystal and the melt 17, the seed was slowly pulled from the melt, using a crystal puller withdrawal rate of about 0.2 inches per hour and a rotational rate of about 30 rpm. At the same time, the temperature of the melt was varied, within the approximate range $1865^\circ\text{C} \pm 10^\circ\text{C}$, to control the diameter of the growing crystal 18. The withdrawal was continued until the crystal was approximately 3.5 inches long by one inch in diameter. At this point, the rotation was stopped and withdrawal was accelerated to about 9 inches per hour until the lower end of the crystal 18 was one half inch above the melt surface. Then, power

15

to the RF coil 13 was shut off, allowing the furnace apparatus 10 and the crystal to cool slowly to room temperature.

The properties of the grown crystal were in excellent agreement with those published in the literature, and shown in the Table. That is, the mullite crystal was orthorhombic (with lattice constants, in Angstroms, of $a=7.55$, $b=7.69$, and $c=2.90$); hardness was 7 Mohs; and the thermal expansion coefficient was 5.0×10^{-6} .

Although the melt used in the present example was stoichiometric, single crystals have also been grown from non-stoichiometric melts.

50

EXAMPLE 2

Akermanite ($\text{Ca}_2\text{MgSi}_2\text{O}_7$)

A charge consisting of CaO , MgO , and SiO_2 in the respective weight percentages 41.13, 14.79, and 44.08 was melted in the iridium crucible 16 at the 1454°C melting point of akermanite. The temperature of the melt 17 was then raised about 70°C to 1525°C. With the crystal puller 19 rotating at about 18 rpm, a seed crystal affixed to the lower end 23 thereof was lowered to a position slightly below the surface of the melt to initiate growth of the akermanite crystal 18 from the melt onto the slightly cooler seed crystal. As the crystal began to grow, the seed was withdrawn from the melt at a rate of 0.2 inches per hour, using a rotation rate of about 18 rpm, and varying the temperature of the melt within the approximate range $1525^\circ\text{C} \pm 20^\circ\text{C}$ to control

55

60

65

the diameter of the growing crystal. The growth conditions were maintained for 20 hours until the crystal was 4.0 inches long by 0.5 inches in diameter. At this point the rotation was stopped and the withdrawal of the crystal from the melt was accelerated to about 8% inches per hour and continued until the bottom of the grown crystal was approximately one-half inch above the melt surface. Then, the furnace apparatus 10 and the crystal were allowed to cool to room temperature.

The resulting crystal was determined to possess a tetragonal crystal structure (with lattice constants $a = 7.8$ Angstroms and $c = 5.0$ Angstroms), and to have the properties: hardness, approximately 5.5 Mohs; thermal expansion coefficient, 5.56×10^{-6} in the [001] direction; and density, 2.99. As in Example 1, all these properties are in excellent agreement with the available published data, which is shown in the Table.

EXAMPLE 3

Gehlenite ($\text{Ca}_2\text{Al}_2\text{SiO}_7$)

A charge consisting of CaO , Al_2O_3 , and SiO_2 in the respective weight percentages 38.67, 38.59 and 22.74 was melted in the iridium crucible 16 at about 1650°C. using a nitrogen atmosphere. The temperature of the melt 17 was then changed about 50°C. to 1600°C. With the crystal puller 19 rotating at about 14 rpm, a gehlenite seed crystal affixed to the lower end 23 thereof was lowered to a position slightly below the surface of the melt to initiate the growth of the gehlenite crystal on the seed crystal from the melt. Upon initiation of the growth, the seed was withdrawn from the melt using a withdrawal rate of about 0.3 inches per hour and a rotation rate of about 14–18 rpm, and varying the temperature of the melts between about 1595°–1630°C. to control the diameter of the growing crystal. These growth conditions were maintained until the crystal was about 3.5 inches long by 0.5 inches in diameter. Rotation was then stopped and withdrawal of the crystal was accelerated to about 8% inches per hour and continued until the bottom of the grown crystal was approximately three-eighths inch above the melt surface. Then, the furnace apparatus 10 and the crystal were allowed to cool at a rate of about 100 C° per hour to room temperature.

The grown gehlenite crystal was transparent and colorless. It was monocrystalline and of tetragonal crystal structure (with lattice constant $a = 7.69$ Å and $c = 5.06$ Å). Other properties of the crystal included: hardness, approximately 6 Mohs; a [001] fast growth direction; refractive indices, $\omega = 1.67$ and $\epsilon = 1.66$; and density, 3.04. Again, these properties are in excellent agreement with the data listed in the Table.

The properties of the crystals grown using the method of the present invention indicate the suitability of melt-grown monocrystalline silicates for use as substrates for epitaxial film-substrate composites. For example, the low thermal expansion coefficient of 5.0×10^{-6} (mullite) and 5.56×10^{-6} (akermanite) indicate that they are more compatible with silicon (3.9×10^{-6}) than sapphire (9.03×10^{-6}). The thermal expansion data shown in the Table are also low, although these data are for polycrystalline silicates, and thus may not always be representative of monocrystalline properties.

Referring further to the Table, the silicon content of the silicates has beneficial effects for composites formed from silicon semiconductor films and silicate substrates. That is, auto-doping should be reduced, and

the stability of the substrate during deposition should be improved, as should the interface adhesion between the film and substrate.

As an example of the compatibility of the silicates for use as substrates, consider gehlenite ($\text{Ca}_2\text{Al}_2\text{SiO}_7$), which was grown according to the method of Example 3. Gehlenite is an excellent electrical insulator, has a thermal expansion which closely matches that of the semiconductor compounds, is chemically compatible with the semiconductor compounds (i.e. minimal or nil auto doping occurs using a gehlenite substrate), is chemically and thermally stable during fabrication and operation, and has rigidity and hardness such that accepted device processing procedures can be employed.

As an additional example of the compatibility of the silicates for use as substrates, cordierite ($\text{Mg}_2\text{Al}_4\text{Si}_5\text{O}_{18}$) has an average coefficient of thermal expansion that closely approximates that of silicon; is resistant to thermal shock; and contains a significant concentration of silicon, thereby providing an expected reduced auto-doping and enhanced adhesion and substrate stability.

Thus, there are grown monocrystalline silicate crystals that have excellent substrate properties. These crystals can be cut or otherwise prepared for the epitaxial growth of semiconductor films thereon. The semiconductor films can then be grown on the silicate substrates using conventional techniques, such as chemical vapor deposition, to produce composite structures or devices. For example, and referring to FIG. 2, a monocrystalline mullite crystal 18 (FIG. 1) was grown in accordance with the present invention and was then cut and polished, using conventional techniques, to form a substrate wafer 26 having an (001) deposition surface 27. Then, an epitaxial (111) silicon film 28 was grown on the deposition surface 27 to a thickness of about 2 μm using pyrolysis of silane in a hydrogen atmosphere and a substrate temperature of about 1000°C. Of course, it will be understood by

those skilled in the art that, regarding silicon-on-mullite orientations, the invention is not limited to {111} silicon on (001) or (001̄) mullite, but also applies to orientations such as {100} or {110} silicon on {100}, {010}, or {110} mullite.

Thus, there has been described a method of growing single crystal silicates from the melt, and usage for the silicates in composites of epitaxial films and substrates. Exemplary compositions, temperatures, times and other parameters for applying the method of the present invention have been given. However, the invention is limited only by the claims appended hereto and equivalents thereof.

Having thus described a preferred embodiment of the invention, what is claimed is:

1. A method of growing single crystal compounds from the class comprising mullite, akermanite and gehlenite selected from the quaternary silicate system $\text{Al}_2\text{O}_3\text{-CaO-MgO-SiO}_2$, comprising the steps of: forming a charge containing weight percentages of Al_2O_3 , CaO , MgO , and SiO_2 corresponding to the weights present in the silicate compound in a suitable reservoir; heating said charge to a temperature that is sufficiently above the melting point of the silicate compound to provide a homogeneous melt; placing a seed crystal of the compound in physical contact with the surface of the melt; and

pulling vertically upward a seed crystal from the melt at (a) predetermined withdrawal rate on the order of about 0.2 to 0.3 inches per hour and a rotational rate on the order of about 14 to 30 rpm.

2. The method recited in claim 1, the compound being mullite, wherein:

said heating step comprises melting a charge containing approximately 72 weight percent Al_2O_3 and 28 weight percent SiO_2 at approximately 1860°-1865°C;

said seed crystal is mullite;

the withdrawal and rotational rates for said pulling step are, respectively, 0.2 in/hr and 30 rpm; and the temperature of the melt is varied within the approximate range 1865°C ± 10°C during said pulling step.

3. The method recited in claim 1, the compound being akermanite, wherein:

said heating step comprises melting a charge containing CaO , MgO and SiO_2 in the approximate weight percentages 41, 15 and 44 at approximately 1454°C, then raising the temperature of the melt to about 1525°C;

said seed crystal is akermanite;

the withdrawal and rotational rates for said pulling step are, respectively, 0.2 in/hr and 18 rpm; and the temperature of the melt is varied within the approximate range 1525°C ± 20°C during said pulling

step.

4. The method in claim 1 including the additional steps of:

pulling the single crystal silicate compound from said melt at an increased withdrawal rate; and allowing said single crystal silicate compound and said melt to cool.

10 5. The method recited in claim 4 including the step of preparing said single crystal silicate compound for the epitaxial growth of a semiconductor material thereon in order to produce a composite structure wherein said single crystal compound is a substrate.

6. The method recited in claim 1, the compound being gehlenite, wherein:

said heating step comprises melting a charge containing CaO , Al_2O_3 and SiO_2 in the approximate weight percentages 38.7, 38.6 and 22.7 at approximately 1650°C., then lowering the temperature of the melt to approximately 1600°C.;

said seed crystal is gehlenite;

the withdrawal and rotational rates for said pulling step are, respectively, approximately 0.3 in/hr and 14-18 rpm; and the temperature of the melt is varied within the approximate range 1595°-1630°C. during said pulling step.
